UNITED STATES PATENT OFFICE.

EDWARD FOSTER CLARK, OF NORTH ATTLEBORO, MASSACHUSETTS, ASSIGNOR, BY
MESNE ASSIGNMENTS, TO CLARK LIGHTER CO., INC., OF NORTH ATTLEBORO, MAS-
SACHUSETTS, A CORPORATION OF MARYLAND.

IGNITER.

Application filed March 1, 1927. Serial No. 171,883.

My invention is an improvement in igniters, more particularly that type of igniter especially adapted for use in lighting cigars, such as is shown, for example in my United States Patent No. 1,594,047, dated July 27, 1926, which is a flint spark, vapor cigar lighter. My present invention is concerned with the vapor or gas producing elements of such a device and is applicable to all vapor igniters or cigar lighters, although specifically described in connection with the cigar lighter of United States Patent No. 1,594,047.

In the drawings:

Figure 1 is an elevation of one side of a cigar lighter;

Figure 2 is a similar view of the opposite side;

Figure 3 is a plan view of the upper end of a lighter;

Figure 4 is a view of a fibre bundle, first stage;

Figure 5 is a view of a fibre bundle, after twisting;

Figure 6 is an enlarged sectional fragmentary view of the burner element;

Figure 7 is a section on line 7—7 of Figure 6;

Figure 8 is similar to Figure 7, but shows the capillary bundle in place within the tube;

Figure 9 is a fragmentary sectional view, enlarged, of a burner and extinguisher.

The lighter is made up of a fuel tank 1, upon which are mounted, in operative relationship, a spark tube 41, within which is carried a flint pressed against a spark wheel 52 by a spring within the spark tube which is compressed between the flint and a screw threaded element 45. The tubular burner 6 stands opposite the spark wheel, actuation of which by thumb wheel 51 throws sparks to the upper end of burner 6 against the capillary element X. When not in use the burner 6 is closed by a swinging extinguisher 8, 83. These elements are all shown and described in my United States Patent No. 1,594,047.

In most lamps and lighters employing liquid fuel the fuel is made available for combustion by means of a wick of woven, braided or felted fabric, one end of which lies in the liquid fuel while the other end is sustained out of the liquid fuel. The liquid fuel is drawn by capillary action through the wick to the sustained end where it is evaporated, when exposed, into the atmos-

phere, the evaporation causing a fresh supply of fuel to travel along the wick by capillarity. If high heat (as a flame or incandescent material) be applied to the sustained end, the vaporized fuel adjacent will be ignited and evaporation greatly increased by the resulting flame which will continue to burn until extinguished or until the supply of fuel fails. When this latter contingency happens the flame will gradually diminish in size and when the fuel is exhausted the exposed wick will be consumed and the flame will then expire for lack of combustible material.

This charring of the exposed end of the wick could be obviated by providing a non-combustible material for the wick, such as asbestos, for example, and this has been tried, but due to the relative coarseness and irregularity of asbestos fibre, asbestos fabric wicks are insufficiently supplied with continuous passages of capillary size and have not proven as useful and satisfactory as cotton, for example, except for certain special uses.

I have discovered however, that the fibres of amiantus, a form of asbestos, may be pressed into bundles of parallel fibres of a desired size and length, the asbestos fibre bundle, under pressure being considerably condensed and the fibres laid in substantially solid parallel contact, and that, by slightly twisting the bundle, the fibrous contact will be disturbed and innumerable minute continuous capillary passages will be opened throughout the length of the bundle.

The fibre bundle forms a capillary member suitable for use in any tubular burner element, such is shown in United States Patent No. 1,594,047. In such a burner or lamp and in such an application or use it is impracticable to provide mechanism for raising a wick at intervals as it is slowly consumed and it is practically important to provide a wick, which after its initial adjustment will not be shortened by gradual combustion. One defect of ordinary vapor cigar lighters has been due to the neglect of users in permitting the fuel supply to become exhausted and the exposed wick consumed until the flame was reduced to a very small size or could not be produced at all.

In addition to the twisted capillary bundle of asbestos fibres and as a further assurance of a liberal supply of fuel to the combustion point, I provide the interior of the tubular

burner element 6 with an irregular surface which prevents the capillary element X from completely contacting with the inner surface of the tubular burner. I have shown in the 5 drawings the interior bore of the burner element provided with a multiplicity of small longitudinal ribs from end to end. These ribs are of a height to take the pressure of the surface of the asbestos bundle and to form 10 capillary spaces or passages between the interior of the burner tube and the exterior of the asbestos bundle, from end to end of the burner tube. The same result would be effected by forming longitudinal slots along the 15 interior surface of the burner, leaving projecting ribs or surfaces between the adjacent slots. I have described these projections and depressions as longitudinal because this is the preferred construction, being cheaper to 20 make and more effective in use, but a multiplicity of projections and depressions of any shape, provided capillary spaces were formed, would be effective.

In Figure 4 I show the capillary gas forming element X as it is first formed and compressed. In Figure 5 I indicate the bundle after twisting. In Figures 6 and 7 the burner element 6 is shown in section, with the interior ribs 61 and depressions or slots 62. In Figure 8, Figure 7 is reproduced with the addition of the capillary element X, showing the longitudinal spaces between the surface of X and the inner surface of the burner.

It will be obvious that even relatively short 35 capillary spaces between the fibres of the bundle X will, due to its helical twist, cross several of the internal ribs or slots of the

burner, so that fuel may find its way from the bundle X to the capillary spaces formed between the surface of the bundle and the interior of the burner. The surface of the bundle X is covered with grooves or spaces of capillary dimensions, between adjacent fibres and these spaces are in operative capillary relation with the opposed inner surface of the 40 burner 6, with its grooves and depressions of 45 capillary size.

I claim:

1. In an igniter, a bundle of asbestos fibres arranged in a parallel, helical relation of the several fibres and having capillary spaces between the fibres and between the bundle and the inner surface of a burner tube; that burner tube, to receive and sustain and cooperate with the bundle to form a capillary 50 gas forming and burning element.

2. In an igniter, a bundle of asbestos fibres, arranged in a parallel, helical relation of the fibres and having capillary spaces between the fibres and between the bundle and the inner 55 surface of a burner tube; that burner tube, provided with a multiplicity of longitudinal interior ribs or slots, to receive and sustain and cooperate with the bundle to form a capillary gas forming and burning element.

3. In an igniter, a burner tube, having an interior bore, and a multiplicity of projections or depressions of capillary dimensions, within the bore, to form connecting capillary spaces from end to end of the tube.

Signed at Boston, Massachusetts, this twenty-fifth day of February, 1927.

EDWARD FOSTER CLARK.
